UNITED STATES PATENT OFFICE.

JOHN ATKINSON STAPLES, OF NEWBURGH, NEW YORK.

FOOT-CONTROL DEVICE FOR AUTOMOBILES.

1,103,095.

Specification of Letters Patent.

Patented July 14, 1914.

Application filed May 2, 1913. Serial No. 765,090.

To all whom it may concern:

Be it known that I, JOHN A. STAPLES, a citizen of the United States, residing at Newburgh, in the county of Orange and 5 State of New York, have invented certain new and useful Improvements in Foot-Control Devices for Automobiles; and I do hereby declare the following to be a full, clear, and exact description of the invention, such 10 as will enable others skilled in the art to which it appertains to make and use the same:

My invention consists in the novel features hereinafter described, reference being had to the accompanying drawings which show one embodiment of the invention selected by me for purposes of illustration and slight modifications thereof and said invention is fully disclosed in the following description and claims.

Referring to the said drawings, Figure 1 is a perspective view partly in section of an embodiment of my invention selected by me for purposes of illustration, applied to 15 the flooring of an automobile, which is shown broken away. Fig. 2 is a top plan view of the parts shown in Fig. 1. Fig. 3 is a sectional view of the same, the position of the operator's foot being illustrated in 20 dotted lines. Fig. 4 is an enlarged plan view of the torsional pedal the positions occupied by feet of different sizes and shapes being indicated in dotted lines. Fig. 5 is a side elevation of the pedal, also showing 25 in dotted lines the positions of the foot of various sizes, with respect thereto. Fig. 6 is a horizontal section through line 6—6 of Fig. 5. Fig. 7 is a detail view of the devices for securing relative adjustment between the 30 pedal, and the devices connected with the part to be controlled. Fig. 8 is a plan view of a slightly modified form of pedal embodying my invention. Fig. 9 is a section 35 on line 7—7 of Fig. 8. Fig. 10 is a longitudinal sectional view of another modification.

The object of my invention is to provide a foot control device for automobiles capable of being operated by the foot of the operator, in which the entire weight and pressure of the foot is supported at all times by the pedal or foot piece, and the adjacent flooring, and in which the foot piece is so constructed that it can be used by any one 50 regardless of the size or shape of his or

her foot, or shoe. The apparatus comprises a torsional pedal, or foot piece consisting of a plate 1 of less length than the foot, having a supporting surface 1^a to engage the sole of the operator's foot and lie substantially beneath the ball of the foot. The plate 1 is provided with a pivotal support, in this instance a pivot stem 2, having its axis substantially beneath the ball of the foot, and disposed perpendicularly to the plane of the plate 1, and the plate is suitably connected to the part to be controlled by the device. In this instance I have shown the pivot stem rigidly secured to the plate and provided at its lower end with an arm 3, provided with a series of apertures 4 for adjustment, and a link 9 extends from one of the holes 4 in the arm to an arm 10 on a valve 12 for regulating the supply of explosive material to the motor, which in this instance is an explosion motor (not shown) but it is obvious that the device may be connected to any other form of mechanism which will control the speed of the motor, and that it may be used with any desired character of motor. A spring 13 connected to the arm 3, and to some stationary part, as an eye bolt 15 secured to the frame 14 of the body of the vehicle, holds the arm, pedal and valve, or other controlled part in normal position and I prefer to provide a stop for limiting the movement of the parts under the influence of the spring. In Figs. 2 and 3 I have shown a collar 16 on the stem 2, having a stop arm 17 secured thereto, and arranged to engage a fixed stop 18 on the flooring or vehicle body.

The pedal is made shorter than the length of the operator's foot so as to permit the heel of the operator to frictionally engage the flooring or other adjacent supporting surface in rear thereof as indicated in the drawings, thus permitting the entire foot of the operator to rest solidly at all times, the sole portion on the pedal, and the heel portion on the flooring in substantially the same plane as the sole engaging or supporting surface of the pedal, so that all strain on the ankle muscles is avoided.

The device is operated by swinging or sliding the heel laterally on a circle concentric with the pivotal connection of the pedal, the heel sliding over the flooring without being raised and the frictional engagement of the heel with the flooring hold-

ing the pedal (and the part controlled thereby) in any adjusted position, thus permitting the utmost refinement of adjustment, as the position of the heel may be varied to any extent from a considerable distance to an almost infinitesimal one, in either direction.

In the practical application of a device of this character a serious problem is prevented owing to the very wide differences between the sizes and shapes of shoes, worn by persons of various sizes, ages and occupations who may drive cars, or a particular car. It frequently happens that a single car may be driven by several persons at different times during the same day, and it is desirable to provide a pedal which can be operated by any one, whether man or woman or child, without the necessity of specially adjusting the control device to accommodate the foot which is to operate it. It is also very desirable to provide means to prevent the longitudinal movement of the foot with respect to the pedal and this adds another complication to the problem of accommodating the pedal to feet of different shapes and sizes.

As a result of study and experiment, I have devised the form of pedal herein shown which will accommodate itself to a very wide range of feet without any adjustment whatever. In arriving at the solution of the problem I have ascertained that the part of the human foot which varies least in length and width is that portion beneath the instep, and I accordingly provide the pedal with a supporting surface 1^a which is designed to support the ball of the foot of the ordinary individual, and extend slightly in rear thereof, and from the rear end of the supporting surface I provide an upwardly extending plate or blade 20 (preferably formed of resilient or spring material) of sufficient length to extend to and engage the forward face of the heel, and having its rear edge 21 straight (or slightly curved upwardly) to engage the heel, close up against the under surface of the instep portion of the sole, the upward inclination of the blade enabling it to do this, and the resilience of the blade enabling it to accommodate itself to a heel of any height from a tennis or golf shoe which has little or no defined heel projection, to a lady's shoe which may have a high French heel. In order to secure the desired operative connection between the pedal and the foot the rearwardly extending blade is provided with some means for positively engaging the foot or shoe, and in the embodiment of the invention herein shown this consists of an actuating projection in the form of an ear or lug 22, which extends upwardly from one side of the blade 20 and also projects preferably in rear of the rear edge 21 of the same. This actuating projection is located on the "pressure" side of the

pedal, that is to say the side toward which pressure is exerted to overcome the tension of the spring and actuate the controlled valve, rheostat or other device connected with the plate. In order to maintain the foot in proper position on the pedal the sole engaging portion 1 is provided on the side opposite the actuating projection, with a vertically extending retaining projection in the form of an ear or lug 6, which is, therefore, located well forward of the actuating device or projection 22. With this construction it will be seen that a shoe of any length, and having any width of sole can be placed on the pedal so as to bring one side of the sole portion against the retaining projection 6, and the front edge of the heel against the rear edge of the yielding or spring blade 20, and the lateral portion of the foot adjacent to the instep against the actuating projection 22, as the projections 6 and 22 are not opposite each other, and the foot can readily be placed in operative relation with the pedal. The blade 20 will yield if necessary to accommodate variations in the height of the arch forward of the heel.

In Figs. 4 and 5 I have illustrated the position which would be occupied by a foot of mean size and proportion, by dotted lines *x*, while in dotted lines *y*, I have shown the position occupied by a woman's foot on the pedal, and in dotted lines *z* I have shown the position occupied by a foot or shoe of unusual size and breadth of sole, any one of which as will be seen will readily accommodate itself to the pedal without any adjustment thereof.

As will be seen in Fig. 4, the difference in the sizes and width of shoes will cause the feet of the operator to assume different angular positions with respect to the pedal. It is also a fact that the feet of different persons set differently with respect to the leg, the toe of one person naturally inclining inwardly and of another outwardly, while with a third the foot may extend directly forward. In order that the operator's foot may assume a perfectly natural and comfortable position on the pedal, and in order to adapt my improved pedal to meet the variations in the "set" of the foot as well as such variations as might be caused by the relation of the size of the foot with respect to the pedal, I have found it desirable to provide for an adjustment of the pedal, to meet these conditions. Such adjustment can be provided in several ways. In my preferred form, I prefer to adjust the pedal bodily about its axis, with respect to the instrumentalities which communicate the motion of the pedal to the valve or other device to be controlled. For example in Figs. 4 to 7, I have shown the pedal adjustable with respect to the supporting pivot, the pivot 2 being provided at its upper end with a cylin-

drical socket 2^a to receive a boss or projection 2^c secured to the lower face of the pedal, the socket and boss being provided with interlocking devices for enabling the pedal to be set in different angular positions with respect to the pivot, without disturbing the connections from the said pivot to the part to be controlled. In this instance the inner face of the socket is cylindrical and provided with a plurality of vertically disposed grooves or recesses 2^b to receive a vertical rib or key 2^d on the lateral face of the boss. Thus should the operator find that the position of his foot when operatively engaging the pedal is not a natural and comfortable one, it is only necessary to raise the pedal to disengage the interlocking devices of the boss and socket, turn it to the right or left as the case may be and drop it into position.

In some instances the actuating projection of the pedal may be made adjustable with respect to the pedal as shown in Figs. 8 and 9, in which said actuating projection, here lettered 22^a, is carried by an arm 23 (preferably of spring material) pivoted to the blade 20^a at 24, and provided with a locking stud 25 to engage one of a series of adjusting apertures or recesses 26 in the blade 20^a.

The blade or rearwardly extending portion is preferably made of spring or yielding material as before stated and may be made integrally with the sole engaging portion of the pedal as shown in Figs. 1 to 9 inclusive, or separately therefrom as indicated in Fig. 10. In this figure the sole engaging portion of the pedal is shown as a casting to which the blade portion 20^a is attached by rivets as shown, or in any other preferred way.

The construction and operation of the device is the same in other respects as previously described.

In order to reduce friction a thin annular bearing surface may conveniently be provided beneath the pedal, around the stem as indicated at 30, or any other form of bearing may be employed to render the operation of the pedal easy, while supporting the entire weight and pressure of the sole of the foot.

It will be seen that with this form of control device any person can step into the automobile and place his or her foot in operative relation with the pedal and operate the machine, regardless of variations in the form or size of the operator's shoe. It will be further noted that the engagement of the blade portion of the pedal serves to hold the foot against longitudinal movement in both directions with respect to the pedal, as the forward face of the heel directly abuts against the rear edge of the blade, and the engagement of the inclined blade against the inclined arched portion of the sole beneath the instep, which inclines downwardly and forwardly from the heel, tends to hold the

foot against rearward movement with respect to the pedal.

What I claim and desire to secure by Letters Patent is:

1. In a foot operated control device, the combination with a pedal, provided with a supporting surface to receive the sole portion of the foot of the operator, of a pivotal support for the pedal located beneath and having its axis disposed substantially perpendicularly to the said supporting surface, and means adapted to connect the pedal with a part to be controlled, said pedal being of less length than the foot to permit the heel of the operator's foot to frictionally engage the adjacent flooring, and to be moved laterally on a circle concentric with said pivotal support to operate said plate without lifting any portion of the foot, said pedal having a lateral projection to engage one side of the sole portion of the foot, and having the supporting surface opposite said projection unobstructed, and means for connecting the pedal at a point in rear of said projection with the operator's foot for joint movement therewith. 80

2. In a foot operated control device, the combination with a pedal provided with a supporting surface to receive the sole portion of the foot of the operator, of a pivotal support for the pedal located beneath and having its axis disposed substantially perpendicularly to the said supporting surface, and means adapted to connect the pedal with a part to be controlled, said pedal being of less length than the foot to permit the heel of the operator's foot to frictionally engage the adjacent flooring, and to be moved laterally on a circle concentric with said pivotal support to operate said plate without lifting any portion of the foot, said pedal having a lateral projection to engage one side of the sole of the foot, and having its supporting surface opposite thereto unobstructed, and an actuating projection located at the opposite side of the pedal, in rear of said first mentioned projection. 110

3. In a foot operated control device, the combination with a pedal provided with a supporting surface to receive the sole portion of the foot of the operator, of a pivotal support for the pedal located beneath and having its axis disposed substantially perpendicularly to the said supporting surface, and means adapted to connect the pedal with a part to be controlled, said pedal being of less length than the foot to permit the heel of the operator's foot to frictionally engage the adjacent flooring, and to be moved laterally on a circle concentric with said pivotal support to operate said plate without lifting any portion of the foot, said pedal having a projection at one side of its sole engaging portion and an actuating projection on the opposite side of the pedal located 120

in rear of said first mentioned projection, the upper surface of the pedal opposite each of said projections being unobstructed.

4. In a foot operated control device, the combination with a pedal, provided with a supporting surface to receive the sole portion of the foot of the operator, of a pivotal support for the pedal located beneath and having its axis disposed substantially 10 perpendicularly to the said supporting surface, and means adapted to connect the pedal with a part to be controlled, said pedal being of less length than the foot to permit the heel of the operator's foot to 15 frictionally engage the adjacent flooring, and to be moved laterally on a circle concentric with said pivotal support to operate said plate without lifting any portion of the foot, said pedal being provided with 20 means for preventing the longitudinal movement of the foot with respect to the pedal; and having projections located at different points longitudinally of the pedal and on opposite sides thereof to engage 25 the side of the foot, the upper surface of the pedal opposite each of said projections being unobstructed.

5. In a foot operated control device, the combination with a pedal provided with a supporting surface to receive the sole portion of the foot of the operator, of a pivotal support for the pedal located beneath and having its axis disposed substantially 30 perpendicularly to the said supporting surface, and means adapted to connect the pedal with a part to be controlled, said pedal being of less length than the foot to permit the heel of the operator's foot to 35 frictionally engage the adjacent flooring, and to be moved laterally on a circle concentric with said pivotal support to operate said plate without lifting any portion of the foot, said pedal having a rearwardly 40 extending portion for engaging the front face of the heel, and having its sole engaging portion provided with a projection at one side thereof to engage the side of the foot, and said rearwardly extending portion provided with a projection on the opposite side to engage the side of the foot, the upper surface of the pedal opposite said 45 projections being unobstructed.

6. In a foot operated control device, the combination with a pedal provided with a supporting surface to receive the sole portion of the foot of the operator, of a pivotal support for the pedal located beneath and having its axis disposed substantially 50 perpendicularly to the said supporting surface, and means adapted to connect the pedal with a part to be controlled, said pedal being of less length than the foot to 55 permit the heel of the operator's foot to frictionally engage the adjacent flooring,

and to be moved laterally on a circle concentric with said pivotal support to operate said plate without lifting any portion of the foot, said pedal having a rearwardly extending yielding portion inclined upwardly and rearwardly from the sole engaging portion, 60 to engage the front face of the heel, beneath the arch of the foot, and having a retaining projection located at one side of the sole engaging portion and an actuating projection located at the opposite side of the 65 said rearwardly extending portion.

7. In a foot operated control device the combination with a torsionally movable pedal, adapted to engage a portion of the bottom of the foot of an operator, said 70 pedal being of less length than the foot to permit portions of the foot not engaged thereby to frictionally engage the adjacent flooring, said pedal being provided with 75 foot positioning means for connecting it to the foot for imparting a torsional movement to the pedal, a pivotal support for said pedal located beneath the same, and substantially perpendicular thereto, means adapted to connect the pedal to a part to 80 be controlled thereby and adjusting means for varying the position of said foot positioning means with respect to the axis of oscillation of the pedal, when the pedal is 85 in normal position.

8. In a foot operated control device the combination with a torsionally movable pedal, adapted to engage a portion of the bottom of the foot of an operator, said 90 pedal being of less length than the foot to permit portions of the foot not engaged thereby to frictionally engage the adjacent flooring, said pedal being provided with 95 foot positioning means for connecting it to the foot for imparting a torsional movement to the pedal, a pivotal support for said pedal located beneath the same, and substantially perpendicular thereto, means adapted to connect the pedal to a part to be controlled thereby and adjusting means for varying the position of the pedal with 100 respect to its axis of oscillation, when the pedal is in normal position.

9. In a foot operated control device the combination with a torsionally movable 115 pedal, adapted to engage a portion of the bottom of the foot of an operator, said pedal being of less length than the foot to permit portions of the foot not engaged thereby to frictionally engage the adjacent flooring, 120 said pedal being provided with foot positioning means for connecting it to the foot for imparting a torsional movement to the pedal, a pivotal support for said pedal located beneath the same, and substantially 125 perpendicular thereto, means adapted to connect the pedal to a part to be controlled thereby and means for adjusting the pedal.

about its axis of oscillation with respect to the said connecting means, to vary the normal position of the pedal.

10. In a foot operated control device the combination with a torsionally movable pedal, means for connecting it to the foot of the operator for imparting a torsional movement to the pedal, a rotary supporting device for said pedal, means adapted to connect said rotary device to the part to be controlled, said pedal and said rotary part being provided with interlocking adjusting devices for varying the normal position of the pedal.
15. 11. In a foot operated control device the combination with a torsionally movable pedal, means for connecting it to the foot of the operator for imparting a torsional movement to the pedal, a rotary supporting device for said pedal, means adapted to connect said rotary device to the part to be controlled, said pedal and said rotary part being provided, the one with a socket and the other with a part fitting said socket, said 25 socket and its engaged part being detachable, and provided with interlocking adjusting devices for varying the normal position of the pedal.
12. In a foot operated control device, the combination with a pedal provided with a supporting surface of less extent than the bottom of the foot, and provided with lateral foot engaging devices located in different transverse planes longitudinally of 30 the pedal and on opposite sides of the same, the surface of the pedal opposite each of said devices being unobstructed, to accommodate feet of different sizes, a pivotal support for the pedal located beneath the same, 35 and having its axis substantially perpendicular thereto, means adapted to connect the pedal to a part to be controlled thereby and means for adjusting said pedal with respect to said connections to vary the normal 40 position of the pedal.
13. In a foot operated control device the combination with a pedal provided with a supporting surface of less extent than the bottom of the foot, and provided with 45 lateral foot engaging devices located in dif-

ferent transverse planes longitudinally of the pedal and on opposite sides of the same, the surface of the pedal opposite each of said devices being unobstructed, to accommodate feet of different sizes, an oscillating pivot shaft for supporting the pedal devices adapted to connect said pivot shaft to the part to be controlled, and means for adjusting said pedal in a rotary direction with respect to said pivot shaft.

14. In a foot operated control device the combination with a pedal provided with a supporting surface of less extent than the bottom of the foot, and provided with lateral foot engaging devices located in different transverse planes longitudinally of the pedal and on opposite sides of the same, the surface of the pedal opposite each of said devices being unobstructed, to accommodate feet of different sizes, an oscillating pivot shaft for supporting said pedal, devices adapted to connect said pivot shaft with the part to be controlled, said pedal and said shaft being detachable and provided with interlocking adjusting devices.

15. In a foot operated control device the combination with a pedal provided with a supporting surface of less extent than the bottom of the foot, and provided with lateral foot engaging devices located in different transverse places longitudinally of the pedal and on opposite sides of the same, the surface of the pedal opposite each of said devices being unobstructed to accommodate feet of different sizes, an oscillating pivot shaft for supporting said pedal, devices adapted to connect said pivot shaft with the part to be controlled, said pedal and said shaft being provided the one with a boss and the other with a socket detachably fitting said boss, said boss and socket having interlocking adjusting devices for varying the relative positions of the pedal and said pivot shaft.

In testimony whereof I affix my signature, in the presence of two witnesses.
